UNITED STATES PATENT OFFICE.

HARRY P. FAIRCHILD, OF NEW YORK, N. Y., ASSIGNOR TO FERMENE G. FAIRCHILD,
OF NEW YORK, N. Y.

MAGAZINE PENCIL.

Application filed May 14, 1924. Serial No. 713,157.

This invention relates to mechanical pencils of the so-called "propel-repel" type, and its chief object is to provide in a pencil of this class a barrel composed of telescoping sections, which can be collapsed to shorten the pencil for convenience in carrying in the vest pocket and can be extended to lengthen it for more comfortable use in writing, and which is equipped with a magazine in which a supply of leads can be carried sufficient for a considerable period of time even when the pencil is in frequent use. A further object is to provide a pencil of the kind indicated, which will stand hard usage without liability of getting out of order. With these objects in view the invention comprises the novel features hereinafter described.

One form of the invention is illustrated in the accompanying drawing, in which—

Fig. 1 is a side view of the pencil, collapsed.

Fig. 2 is a side view showing the barrel extended or lengthened for writing, portions of the two sections of the barrel being broken away to show the enclosed parts.

Fig. 3 is a longitudinal section showing the mechanism by which the lead is advanced and retracted, and also showing the relation of the lead magazine to the mechanism when the barrel is collapsed.

Fig. 4 is a cross section, about on line 5—5 of Fig. 3.

Fig. 5 is a detail longitudinal section of the writing end of the pencil, showing the operation of ejecting or expelling the lead.

Fig. 6 is a detail cross section, about on line 6—6 of Fig. 2, illustrating an advantageous feature of the invention.

The pencil illustrated comprises a tapered writing tip 10, and a barrel composed of a forward or outer section 11 and a rear or inner extensible section 12, the tip and barrel being rotatable relatively to each other as is customary in propelling pencils. Fixed to the tip and extending rearwardly into the barrel section at the center or axis thereof is a tube 13, having a helical slot 14, and fitted smoothly on the outside of this helically slotted tube is a tube 15 having a straight longitudinal slot 16. Inside of the inner tube 13 is a tubular clutch 17, in which the rear end of the lead is inserted and held, and which is provided with a rear lug 18 extending radially into the two slots 14 and 16. In the clutch tube 17 is a plunger 19, projecting rearwardly and equipped at its rear end with a lug 20, extending into the two slots 14 and 16 in rear of the lug 18. Assuming that the tubes 13 and 15 can be rotated relatively to each other but cannot move lengthwise, it will be seen that rotation of the inner (helically slotted) tube in the direction of the arrow in Fig. 5 will cause the clutch tube 17 and plunger 19 to move together toward the tip 10, thereby advancing the lead, which is shown at 21, and that rotation in the opposite direction will retract the lead.

At its forward end the longitudinal slot 16 in tube 15 has a short lateral recess or circumferential extension 22, Fig. 5. Then when the clutch 17 has been advanced, as described above, until the lug 18 has reached the forward end of slot 16 the clutch can advance no further, and the lug turns into the lateral recess; but the lug 20 on plunger 19 can still advance, thereby pushing the plunger ahead and causing its forward end to expel or eject the lead from the clutch. When the parts are rotated in the opposite direction the reverse movement takes place, as will be readily understood: the plunger is first retracted, thereby permitting a fresh lead to be inserted into the forward end of the clutch, after which the clutch itself is retracted.

For convenient actuation of the mechanism described above, the enlarged forward end 23 of the screw or helically slotted tube 13 is soldered or otherwise fastened to the tapered tip 10, and the guide bushing 24, which extends into the tip 10, is soldered to the barrel section 11 and also to the end of the longitudinally slotted tube 15. It will therefore be seen that rotation of the tip 10 relatively to the barrel, or vice versa, will cause relative rotation of the helically and longitudinally slotted tubes, thereby causing the described movement of the lead. Lengthwise displacement of either tube relatively to the other is prevented by the collars 25 and 26 soldered on the ends of tube 13. The tip 10 and barrel section 11 are thus rotatable relatively to each other but are inseparable lengthwise.

The telescoping barrel section 12, which slides inside of the forward section 11, encloses a magazine tube 27, shown in Fig. 4 as being in cross section similar to a six-

pointed star, soldered or otherwise secured to the barrel section 12 and fitting snugly therein to provide cells 28 for the individual leads 29. These cells are closed at the forward end by a ring 28^a soldered to the tube 27. On the rear portion of the longitudinal slotted tube 15 is a lug or rib 30 extending into one of the grooves between the ribs on the magazine tube 27, as indicated in Fig. 3. It will therefore be seen that the inner telescoping barrel section 12 can be drawn rearwardly out of the main section 11, carrying with it the magazine 27, and that lengthwise separation of the barrel sections is prevented by the lug or rib 30, which lies in the path of the ring 28^a. In the pencil shown the hexagonal shape of the telescoping barrel sections makes relative rotation of these snugly fitting parts impossible. If the barrel sections were cylindrical, such movement would be prevented by the lug or rib 30, as will be readily understood, since this rib extends into one of the inner grooves of the magazine tube 27 and the latter is fixed to the barrel section 12. The rear end of the magazine tube is extended slightly beyond the tubes 13 and 15 to receive a short screw 31, which is fixed in the end of the magazine by solder 31^a or other convenient means. The lead cells 28 are closed at the rear by removable cap 32 threaded on to the screw 31. This cap also affords convenient grasp for the fingers when the user desires to lengthen or shorten the pencil by telescoping movement of its parts.

In the form illustrated in Fig. 6 the sliding longitudinally slotted tube 15 is formed with one or more ribs 15^a (in the present instance three) extending its full length and fitting in the inner corrugations of the magazine tube 27 so as to slide therein. In this construction, which affords great strength and smoothness of operation, the lug 30 (Figs. 2 and 3, not shown in Fig. 6) serves merely as a stop to prevent the telescoping barrel-section and magazine from being drawn entirely off.

From the foregoing it will be seen that when the barrel sections are telescoped together the pencil is short enough to be carried conveniently in a small pocket or in a small purse, but that it can be extended to a convenient length for writing as in Fig. 2, merely by pulling on the cap 32. To actuate the lead, that is, to advance, retract or expell the lead, it is not necessary that the barrel be collapsed; and since the magazine is carried by the rear of inner barrel section,

access to the magazine for removal of leads can be had with this section extended as well 60 as in the collapsed position.

It is to be understood that the invention is not limited to the construction herein specifically illustrated and described but can be embodied in other forms without departure 65 from its spirit as defined by the appended claims.

I claim—

1. A magazine pencil having, in combination, a longitudinally extensible and collapsible barrel composed of relatively telescoping main and rear sections, lead actuating mechanism housed within said main section of the barrel and longitudinally stationary therein, and a magazine carried by the rear section of said barrel and slidable within the other section, said magazine surrounding and sliding over the lead actuating mechanism between the latter and the main barrel section in the telescoping movement of said sections. 70 75 80

2. A magazine pencil having, in combination, a barrel composed of a main section and a rear telescoping section, mechanism extending lengthwise of the main barrel section and having parts rotatable relative to each other to advance and retract the lead, a magazine carried by the telescoping section and surrounding said mechanism, and means connecting the magazine with one of the relatively rotatable parts of said mechanism to rotate said part when the telescoping barrel section is rotated, and permitting sliding movement of said mechanism and telescoping barrel sections relative to the main 95 barrel section. 85 90 95

3. In a magazine pencil, in combination, a barrel comprising a main section and a rear section telescoping into the main section, mechanism extending lengthwise of the main 100 barrel section and having parts rotatable relative to each other to advance and retract the lead, a rotatable writing tip at the forward end of the main barrel section, one part of said lead advancing and retracting 105 mechanism being connected to said tip and the other to said main section, a lead magazine carried by the telescoping section of the barrel and surrounding said mechanism, and means for operatively connecting said telescoping section and one of said relatively 110 rotatable parts.

In testimony whereof I hereto affix my signature.

HARRY P. FAIRCHILD.
